UNITED STATES PATENT OFFICE.

JOSEPH S. LAUNDERVILLE, OF OAKLAND, CALIFORNIA.

SELECTIVE COIN-OPERATIVE DEVICE.

Application filed April 21, 1921. Serial No. 463,414.

To all whom it may concern:

Be it known that I, JOSEPH S. LAUNDERVILLE, a citizen of the United States, and resident of the city of Oakland, county of 5 Alameda, and State of California, have invented new and useful Improvements in Selective Coin-Operative Devices, of which the following is a specification.

My invention has for its object a container having several compartments in each of which there is a plurality of small articles, such as balls of gum, candy or the like and which several compartments may be charged with different sizes or flavors or 10 other varying qualities to satisfy the varying tastes of the public and which may be selectively abstracted by the insertion of a coin and movement of a lever. The device is particularly adapted to being exposed on 15 counters and the like and is provided with means by which a unit of merchandise is transferred from its compartment into a pocket exposed to the operator whenever the requisite coin has been deposited 20 and the operating device moved. In this way a purchaser may insert the coin into any pocket of which he desires to abstract the corresponding merchandise, operate the lever and the machine will discharge to him 25 one unit of said merchandise and will thereafter restore itself ready for a second operation, which second operation may only be performed after the introduction of another coin. The coins as passed into the machine, 30 are retained in a separate compartment and the merchandise is arranged behind glass so as to be readily observable to an intending purchaser.

By referring to the accompanying drawings my invention will be made clear.

Fig. 1 is a side view of my machine as particularly constructed and adapted to the sale of balls of gum of different flavors.

Fig. 2 is a cross section of Fig. 1 on the line II-II thereof, and showing the openings through which the gum is passed to the operating mechanism.

Fig. 3 is an enlarged section through the lower portion of the apparatus of Fig. 1, 50 showing the interior construction and operating mechanism and manner in which the coin is employed to release the merchandise.

Fig. 4 shows in plan certain of the operating parts of Fig. 3 with certain of the sta-

tionary parts thereabove shown in dotted lines.

Fig. 5 is a cross section through the casing on the line V-V of Fig. 6.

Fig. 6 is a front view of a small portion of the casing adjacent to the operating lever 60 in its position of starting and showing the coin slot thereabove.

Fig. 7 is a plan view of the operating lever and its center construction as employed in combination with each of the compartments. 65

Fig. 8 shows a variation in construction whereby a single lever is used to actuate the mechanism under any or all of the pockets depending on the inserted coin or coins.

Fig. 9 is a plan view with top portion of 70 the machine removed to better disclose the arrangement and operation of the parts.

Throughout the figures similar numerals refer to identical parts.

A glass globe is indicated by the numeral 75 1 open at the top and bottom and having partition members 2, 3, 4 therein forming a plurality of compartments. These partition members extend into the bottom and are preferably mounted in grooves as at 5, Fig. 80 3, which latter extend upward from the bottom member 6. In the device chosen for illustration and having the three compartments formed by the partitions 2, 3, 4, the bottom 6 is formed with three openings 7, 8, 85 9, through which the little balls of gum 10 may readily drop until they contact with the operating lever member 11, (see also Fig. 7) and at such time occupy the position shown in Fig. 3 within an opening in the circular 90 plate 12. This latter is pivoted at 13 and said pivot I prefer also to extend through the operating member 11, thus forming likewise a pivot for said member, and to be secured to the bottom plate 14. The pivot 13 95 is preferably shouldered at 15 and provided with a holding nut 16 thus forming also a spacing member between 6 and 14 which are thus tightly bolted together while the plate 12 and operating member 11 are freely moveable therebetween.

Extended out from the member 11 is the operating handle 17 exposed outside of the casing for the hand of the operator. At 18 I prefer to introduce a bushing about the center rod 19 which also insures the proper spacing of 6 and 14. At 50 is a chute which terminates in a pocket for receiving such

balls of gum as may be passed from the circular member 12 and through plate 14 as will be described below, and the center rod 19 I employ to clamp the several parts together. The top 20 may be locked in any well known way as by the padlock at 21. The casing is shown in two parts 22 and 23 respectively, and in the upper portion 22 I form the coin slot 24 by which a coin may be introduced and travel downward as on the dotted lines 25, thus falling into the slot 26 of the block 27 formed with the operating lever 17. At such time the coin is resting on the incline 28 and upon the bottom plate 14 and projects into the slot 29 of the circular member 12. See Figs. 3 and 4. It will now be apparent that if the operating lever 17 is moved in the direction of the arrow 30 it will carry with it the coin 31, whose edge will slide upon the bottom 14 and whose side resting in the slot 29 will carry the circular member 12 in the direction of the arrow 30 and the ball of gum 10 will at such time be carried beyond the range of the opening 9 and into the portion of the opening 37 at which time the spring 33 will snap into the recess 34, thus holding the circular member 12 from returning when the lever 17 is moved in the direction opposite to the arrow 30. When handle 17 is turned after the insertion of a coin, disc 12 and member 11 would move together until spring 33 snapped into a notch 34, which would occur at about the time the handle 17 reached the end of its strokes. At that time ball 10 would reach the position indicated by the opening 37 and drop through the aperture in member 14. Handle 17 with member 11 would return to normal position while 12 remained stationary and another ball would drop into aperture 36. The spring 33 is anchored as at 38 to the bottom member 6 and the range of movement of the lever 17 is through a slot formed in the side of the casing as at 39, Fig. 6. The upper and lower sections of the casing I prefer to form with the tongue and groove jointed as shown at 41 in Fig. 5, thereby aligning the parts together. It will also be apparent from the construction shown that the center bolt 19 may if desired be swiveled at 40 or elsewhere in combination with the lower casing 23 so that the entire upper structure above 23 may rotate to bring any part of the globe 1 to the front, at which time the upper casing 22 will rotate on the lower casing 23 as about the joint 41. The coin 31 which falls into the slot 26 (see Fig. 4) is carried in the direction of the arrow 30 when the lever 17 is moved and carries with it as above stated the rotating member 12 until such time as the said coin resting upon the plate 14 arrives opposite to the slot 42, when the coin falls through the said slot 65 thus disconnecting any movement between 17 and 12. At this time, however, the spring 33 has engaged one of the ratchet openings in the periphery of the member 12 so that the latter is held from returning and the coins falling into the bottom pan 43 are collected and may be removed by unlocking the bottom as by the padlock engaging the lugs 44. The ball of gum falling through the opening 37 in the plate 14 descends on the sliding chute until it arrives in the exposed 75 pocket at the end of the chute 50.

Apertures 7, 8, 9 of Fig. 2 are in the member 6 and do register with one or more openings in the discs to insure the discs being charged. See Fig. 4. They do not, however, 80 register with the openings as 37; a rotation of the respective discs being necessary in each case to transfer the charge in any disc pocket to the opening 37.

Referring particularly to Fig. 9 wherein 85 I have shown a variation of the mechanical construction in my coin operative device; 45 indicates an annular ring or plate member which is operated in a rotary direction by the lever 46 between limits 47, 48 and about 90 a central axis of rotation 57. Three members are indicated at 60, 61, and 62 and are respectively pivoted at 63, 64 and 65 to the bottom plate 14 and have superimposed thereover the discs, 66, 67 and 68: pins and 95 slots connecting the members and ring 45 are shown at 49, 51 and 56 respectively. These discs have holding springs and slots 72, 73, 74, whereby the discs 66, 67 and 68 are permitted to be rotated in one direction 100 only and are frictionally held by their respective springs. A retracting spring is supplied at 75 to return the handle 46 against stop 47. Coin slots are provided for each disc and member as at 76, 58, 79, respectively, so that as a coin is introduced it forms 105 an engaging means between the corresponding disc and member. When a coin is inserted a movement at 46 rotates the corresponding member and disc until the coin arrives over its discharge opening as 42, Fig. 4. No rotation is imparted to any disc unless a coin be inserted in the appropriate slot as above described and the handle 46 thereafter operated.

It will now be seen that by dropping a coin in any of the selected slots and opposite the particular merchandise unit and then 110 operating the common lever or handle 46 that the single selected unit will be discharged and the coin released and that no further units may be abstracted until another coin is inserted in one of the slots.

I claim:

In a coin operative device, a receptacle 115 having a plurality of compartments opening downward adapted to hold different merchandise units, a disc rotatable under each of said openings and having a plurality of passages, one of which passages registers 120

with the corresponding compartment opening, an oscillating member under each disc and a common pivot for the disc and member, a coin slot common to each disc and its member, a bottom element having passages adapted to retain a coin in any of said slots and clearance openings in said element for dis-

charging the coin from any corresponding slot when the member has rotated the disc to register a disc passage with a corresponding passage in said element whereby a unit of merchandise is discharged and operating means common to all of said members.

JOSEPH S. LAUNDERVILLE.
